RADIO APPARATUS

John D. Reid, Highland Park, Pa., assignor to
 Radio Corporation of America, a corporation of
 Delaware

Application November 30, 1932, Serial No. 644,951

8 Claims. (Cl. 250—20)

My invention relates to radio apparatus and, more particularly, to radio receivers adapted to cover a wide frequency range.

In order that broadcast receivers designed to cover the frequency-range between 550 and 1500 kilocycles may be utilized for the reception of signals at higher frequencies, it has been proposed to first heterodyne the incoming signals down to some frequency within the broadcast range before impressing them upon the receiver. This has previously been accomplished through the use of an auxiliary device popularly known as a converter, which is connected between the antenna and the radio receiver, the latter thus functioning to amplify and rectify the beat frequency.

It is customary to provide the converter with a continuously variable oscillator and with a detector, the tuning of which is also continuously variable, the several tuning devices, usually variable condensers, being interconnected for simultaneous operation and a single indicating scale being utilized to indicate the tuning.

In order that a number of short-wave bands may be covered, converters, as a rule, have been provided with a plurality of interchangeable inductors of the plug-in type. Since the same tuning condensers are used, however, irrespective of the particular band it is desired to cover, such converters have a rather serious drawback, namely, the crowding together of the frequency-channels with respect to the dial-scale as the inductance of the coils decreases.

That such is unavoidably the case is apparent from a consideration of the formula indicating the range that may be covered by a tunable circuit constituted by a fixed inductor and a variable condenser as the latter is varied from its maximum capacity position to the position of minimum capacity, i. e.,

$$f_2 - f_1 = \frac{1}{2\pi\sqrt{L}} \left(\frac{1}{C_2} - \frac{1}{C_1} \right)$$

wherein the subscripts 1 and 2 indicate, respectively, the low and high frequency ends of the range. Obviously, as the inductance of the coil is lowered, the range increases, with the result referred to above, namely, the channels become so crowded with respect to the dial calibration that tuning and logging become more and more difficult.

It is, accordingly, an object of my invention to provide a radio receiving system that shall not be open to the objections noted above.

Another object of my invention is to provide

a radio receiving system that shall be capable of covering widely separated frequency ranges without the use of plug-in coils.

Another object of my invention is to provide a combined long-short wave radio receiver that shall be more efficient on the several frequency ranges than analogous receivers heretofore known.

The foregoing objects and other objects ancillary thereto, I prefer to accomplish through the use of a broadly tuned frequency-converter, preceding a sharply tunable radio receiver, rather than through the use of a continuously tunable converter as heretofore. In short, my improved converter system is so designed that, through the use of a plurality of multi-contact switching devices, incoming signals lying in any one of a plurality of short-wave bands may, simultaneously, be heterodyned down to frequencies falling within the 550-1500 kilocycle range of the usual broadcast receiver, the adjustment of the receiver proper being relied upon to separate the desired signal from those undesired.

The novel features that I consider characteristic of my invention are set forth with particularity in the appended claims. The invention itself, however, both as to its organization and its method of operation, together with additional objects and advantages thereof, will best be understood from the following description of a specific embodiment when read in connection with the accompanying drawing, in which

Fig. 1 is a diagrammatic view of a radio receiving system including a preferred embodiment of my invention, and

Fig. 2 is a rear elevational view of a commercial broadcast receiver modified according to my invention.

Referring to the drawing, a radio receiving system including a preferred embodiment of my invention is constituted by a frequency converter portion 1, and a radio receiver portion 3, the latter, preferably, being of the uni-control super-heterodyne type. The converter portion is constituted by a detector tube 5, and an oscillator tube 7, each tube being provided with input and output circuits whereby incoming radio signals and locally generated oscillations may be combined to form beat frequencies.

The detector tube, in order that maximum sensitivity may be had, is preferably of the screen grid pentode type having an anode 9, a suppressor grid 11, a screen grid 13, a control grid 15, a cathode 17, and a heater 19. The oscillator tube may be of the three-electrode type having

an anode 21, a control grid 23, a cathode 25, and a heater 27.

Since, according to my invention, I cause a plurality of incoming signals falling in a definite frequency band to be simultaneously heterodyned, I provide the detector tube and the oscillator tube not with variable tuned input circuits, but with broadly tuned circuits which may be varied in a step-by-step manner to select the desired frequency band. Specifically, the input circuit of the detector tube is constituted by an inductor 29, one end of which is connected to the control grid of the detector and the other end of which is connected through a conductor 31 to the chassis 32 of the converter portion. The inductor is provided with three intermediate taps from which leads extend, respectively, to switch points designated in the drawing 33, 35, and 37. A plurality of capacitors 33, having a capacity of at least 5000 mmf. are connected between the cathodes of the detector and oscillator tubes and the conductor 31. These capacitors are for the purpose of providing a by-pass for currents at radio frequencies, the presence of which would normally cause a heater supply frequency hum to appear in the output of the system.

A fourth switch point 39 is provided, to which no part of the system is permanently connected, and a fifth point 41, from which a connection 43 extends to the control grid of the input inductor. Associated with the switch points is a movable contact member 45, connected to the chassis and the low potential end of the input conductor over the conductor 31.

An adjustable capacitor 47 is connected in shunt to the entire input inductor and, depending upon with which of the points 33, 35, 37, and 39 the movable contact member 45 is associated, the input circuit is tuned to approximately the middle of any one of four short-wave bands. The switch-point 41 directly connected to the grid end of the inductor is utilized to short-circuit the input inductor in the event that it is desired to receive signals, in the broadcast band, directly upon the radio-receiver portion 3 of the system. The manner in which this is accomplished will be more fully explained hereinafter.

It will also be noted from an inspection of the drawing that the cathodes of the oscillator and first detector tube are connected to the chassis of the converter through a self-biasing resistor 49 shunted by a condenser 51 whereby the control-grids thereof, when the converter is in operation, are maintained at a negative potential 55 with respect to the cathodes thereof.

The oscillator is provided with an input inductor 50 with which are associated a plurality of semi-fixed tuning capacitors 50, 53, 55, and 57, one terminal of each of the capacitors being connected to the grid end of the inductor, and the other terminals thereof being conductively connected, respectively, to a plurality of switch points 59, 61, 63, and 65. A feed-back inductor 66, in the anode circuit of the oscillator, is coupled to the input inductor 50.

The low potential end of the oscillator input inductor is connected to the converter chassis over the conductor 31, as is also a movable member 67 which contacts the switch points.

An additional switch point 69, analogous to the point 41, is provided whereby the oscillator input inductor may be short-circuited simultaneously with the detector input circuit.

An inductor 70, included in the screen-grid circuit of the detector tube, is inductively cou-

pled to the oscillator input and output inductors, whereby locally generated oscillations may be impressed upon the detector.

An antenna inductor 71 is coupled to the detector tube input inductor, one end of the coil terminating in a binding post 73 or a flexible lead adapted to be connected to an antenna, and the other end being connected to an elongated switch point 75, or to a plurality of inter-connected points, (not shown), corresponding in arc to the first four positions of the switching devices associated, respectively, with the detector tube and the oscillator tube.

An additional unconnected switch point 77 is also provided. With the points 75 and 77 is associated a movable contact member 79 connected to the converter chassis over the conductor 31.

The several switches are connected together for simultaneous actuation as indicated by a dotted line 81 on the drawing.

The converter is supplied with screen grid, anode, and heater potentials from the potential supply system in the radio receiver proper.

The radio receiver which I have chosen to exemplify my invention is of the uni-control super-heterodyne type having a radio frequency amplifier tube 83, an oscillator tube 85, a first detector tube 87, an intermediate frequency amplifier tube 89, a second detector tube 91, and an output or power amplifier tube 93. Since receivers of this general type are now well known to those skilled in the art, no necessity is seen for illustrating the various circuit connections whereby the radio and intermediate frequencies are transferred from tube to tube and the several tubes are supplied with cathode, anode, and grid biasing potentials. Also, the receiver need not necessarily be of the uni-control type, though this is desirable, since the specific manner in which the radio frequency circuits and the oscillator circuit of the standard wave receiver are tuned forms no part of my present invention. It is fairly important, however, that the input or antenna coil of the receiver have a natural frequency below the low end of the range from which the receiver tunes, for best results.

In the specific receiver illustrated, the output tube 93 is of the screen grid pentode type having a cathode-heater 95 supplied from a secondary winding 97 on the main power transformer in the receiver and being supplied with screen grid potential from the receiver rectifier, (not shown), over a conductor 99.

In order that the converter portion of my improved receiver may be provided with screen grid, anode and heater potentials, I interpose an adaptor plug 101 between the prongs of the output tube 93 and its socket, (not shown), the several potentials then being available to the converter over conductors 103, 105, and 107, respectively, which extend from the adaptor.

The screen grid of the detector tube and the anode of the oscillator tube are supplied with lower potentials than the anodes thereof, a resistor 109 being interposed in the potential supply circuit for that purpose.

I also connect the chassis 32 of the converter to the ground terminal and chassis of the radio set by means of a conductor 111.

Referring to the drawing, it will be noted that the detector tube in the converter is supplied with anode potential from the conductor connecting to the screen grid of the output tube in the radio receiver portion over a circuit which includes the input inductor 113 of the receiver.

It will also be noted that, when the movable contact member 79 associated with the detector input circuit is in any one of the first four positions, an inductor 115 and a condenser 117 are effectively connected in shunt to the input inductor of the receiver, as indicated in dotted lines. The inductor is of such size that, when so connected in shunt to the input inductor, the two inductors in parallel have a natural resonant period lying approximately in the middle of the range of beat frequencies which the converter is intended to develop.

During the reception of short waves, the converter functions to simultaneously heterodyne a plurality of incoming signals, depending upon the position of the movable switch arms, and a plurality of beat frequencies are simultaneously impressed upon the receiver portion. The constants of the system are so chosen that, irrespective of the band being covered, the beat frequencies produced fall within the tuning range of the receiver and the separation of the desired signal from those undesired is accomplished through adjustment of the tuned circuits in the receiver. The radio receiver portion, therefore, may be tuned, as usual, and, although the input signal thereto is not the original short wave itself, but a beat frequency produced therefrom, the receiver-dial markings, if calibrated in 10 kc. divisions, still represent 10 kilocycle separation.

Referring to Fig. 2 of the drawing, which is a back view of a commercial radio receiver modified according to my invention, I find it expedient to mount the converter unit 1 upon the inner surface of one of the side walls 119 of the cabinet. All of the apparatus constituting the converter, with the exception of the detector and oscillator tubes, is enclosed within a shielding container 121 and I also find it preferable to enclose the tubes in individual shields 123 and 125 for the purpose of minimizing pickup from local broadcasting stations during short-wave reception. The shielding container constitutes the chassis 32 of the converter portion referred to above.

The several switches in the converter unit are "ganged" together, and an actuating shaft 127, carrying a knob 129, and an indicating pointer 131, extends through the cabinet wall in order that the said converter may be adjusted for the different frequency ranges. Although not shown in the drawing, an appropriately inscribed escutcheon plate surrounds the switch actuating knob 129 to indicate which of the tuning ranges the receiver is adjusted to cover.

In a preferred embodiment of my invention, the band waves covered by the converter when the switch is in the first four positions are respectively 15,340 to 15,000 kc.; 11,900 to 11,700 kc.; 9,600 to 9,500 kc.; and 6,150 to 6,000 kc. In each case, the band width in kilocycles is not greater than 250 kc., which range is easily handled by the usual radio receiver that is designed to cover the standard broadcast range of 1,500 to 550 kc.

Since all tuning adjustments are effected from the switch and the tuning of the radio receiver portion, it will be appreciated that considerable interference with short-wave reception may be caused by nearby powerful long wave broadcasting stations. Such interference may be eliminated in each range by shifting the oscillator frequency, resulting in an equal shift in receiver dial setting. This result is accomplished by adjusting the semi-fixed condensers associated

with the oscillator to values best suited to local conditions.

It is also highly desirable that all leads between the converter portion and the radio receiver portion be effectively shielded and that the shielding braid be grounded into the receiver chassis.

Under certain conditions, where local interference from long wave broadcasting stations is particularly difficult to obviate, I find it desirable to utilize a short antenna, of from 15 to 30 feet in length, for short wave reception. I also have attained excellent results by including a wave trap 132 in the connection to the short-wave antenna, as shown in dotted lines in the drawing. This trap may be so constructed as to attenuate the entire broadcast band, or it may be specifically designed to reject the most troublesome interfering stations.

Since the short antenna, when connected as described, will not operate satisfactorily for long wave reception, an additional antenna connection 133 to the switch point 75 is provided. This antenna serves as additional ground area during short wave reception, and, if desired, it may be erected to function as a counterpoise.

Furthermore, the receiver itself, preferably, should not include any exposed coils which function at radio frequency and it is very desirable that no unshielded leads be outside of the chassis shield.

It will be apparent from the foregoing description of my improved receiver that its principal advantage lies in the uniformly greater separation of short-wave stations on the tuning dial that is obtainable. An outstanding feature, also, is that the same dial in the radio receiver portion is used for tuning both the short and long wave bands and the dial divisions always represent 10 kc. This gives excellent separation of the short wave stations, and greatly increases the ease with which they may be tuned in and logged.

Although I have shown and described certain specific embodiments of my invention, I am fully aware that many modifications thereof are possible. My invention, therefore, is not to be restricted except insofar as is necessitated by the prior art and by the spirit of the appended claims.

I claim as my invention:

1. In a radio receiver, a broadly tuned frequency converter portion, a relatively sharply tunable beat-frequency amplifier portion, switching and circuit means for effecting a connection for an energy collector to either portion, at will, and means simultaneously operable with said switch means for altering the input circuit constants of said amplifier portion, and said first named means including a permanent connection between the amplifier portion and the connection for said energy collector.

2. In a radio receiver, a broadly tuned frequency converter portion, a relatively sharply tunable beat-frequency amplifier portion, a plurality of antennae, switching and circuit means for at will connecting one of said antennae to the frequency converter portion and grounding the other antenna or removing the ground connection from the last-mentioned antenna and effectively coupling it to the input circuit of the beat frequency amplifier portion, and means providing a connection for the frequency converter portion with the input circuit of said beat frequency amplifier portion.

3. In a signal receiving system, a receiver

tunable through a predetermined frequency range and having an input circuit provided with an input inductor, a frequency converter, an antenna circuit and an output circuit for said converter coupled jointly to said inductor, means for decoupling said antenna circuit, selector means for tuning said frequency converter to provide a plurality of beat frequency signals, means for tuning said input circuit to a predetermined frequency, and means for rendering said frequency converter inoperative to produce beat frequency signals.

4. The combination with a tunable radio receiver having a signal input circuit, of a broadly tuned frequency converter comprising an electric discharge oscillator tunable selectively to each one of a plurality of different signal frequencies, a switch for effecting said selective tuning, a detector coupled to said oscillator, said detector having an output anode circuit connected with said receiver input circuit, a tuning inductor for said input circuit, an antenna circuit coupled to said detector through said anode circuit connection, means for selectively tuning said detector to each one of a plurality of signals at differing frequencies, said selecting means including a switch, selector means for connecting said antenna circuit to ground and said tuning inductor across said input circuit, said last-named means including a selector switch, and means for simultaneously operating said switches.

5. In a radio receiving system, an oscillator circuit comprising an inductor, a plurality of semi-fixed tuning condensers therefor and a selector switch for selectively connecting each of said condensers with said inductor to tune it, a detector comprising an electric discharge device having a signal input grid and an electrode other than said grid coupled to said oscillator inductor, an input circuit for said detector comprising a second inductor and selector means for tuning said inductor to a plurality of different signal frequencies, an antenna circuit coupled to said last-named inductor, means for grounding said antenna circuit through said coupling means, an output anode circuit for said detector connected with the receiver input circuit, means providing a signal conveying connection between the antenna cir-

cuit and said receiver input circuit through said output anode circuit connection, and a tuning inductor for said input circuit in said last-named connection.

6. In a radio receiver, a broadly tuned frequency convertor portion, a relatively sharply tunable beat-frequency amplifier portion, and switching and circuit means for effecting a connection for an energy collector to either means, said last named means including a coupling winding adapted to be connected at one end to an energy collector, a coupling circuit connected to the opposite end of said winding and to said beat-frequency amplifier portion, and said switching means including contacts for grounding said last named end of the coupling winding when operating in a predetermined higher frequency range.

7. In a radio receiving system including a tunable signal receiving portion and a frequency convertor portion, the combination of a frequency convertor tube in said last named portion having an output anode circuit coupled to said tunable signal receiving portion, an antenna circuit coupled to the input electrode of said frequency convertor tube and including a coupling winding, one end of which is connected to the anode circuit through a series condenser and high frequency choke coil, and switching means for selectively connecting said end of the coupling winding to ground.

8. The combination with a radio receiver having a signal input coupling inductor, of frequency converter means including an electric discharge detector device having an output anode, a control grid and a second grid between said control grid and the output anode, a signal input circuit connected with said control grid, an oscillator connected with said second grid, an anode circuit including said input inductance connected with said anode, an antenna circuit including a coupling inductance and a high frequency choke coil in series with said input inductance through connection with said anode circuit, and switching means for grounding the connection between said antenna inductance and said high frequency choke coil.

JOHN D. REID.
